UNITED STATES PATENT OFFICE.

COSMAN HENRY COHEN, OF LONDON, ENGLAND.

MACHINE FOR SETTING OFF IMPRESSIONS ON GLASS OR OTHER BRITTLE SUBSTANCES.

SPECIFICATION forming part of Letters Patent No. 665,180, dated January 1, 1901.

Application filed July 9, 1900. Serial No. 23,037. (No model.)

To all whom it may concern:

Be it known that I, COSMAN HENRY COHEN, a subject of the Queen of Great Britain, residing at London, England, have invented new and useful Improvements in Machines for Setting Off Impressions on Glass or other Brittle Substances, of which the following is a specification.

My invention relates to certain machines for setting off on sheets or slabs of glass and other brittle substances impressions taken from lithographic stones, engraved blocks, and the like, the kind of machines to which my said invention is applicable being such as embody the essential features of construction described in the specification of Letters Patent of the United States of America No. 595,525, granted to me and dated the 14th day of December, 1897—that is to say, machines so constructed that the article or articles from which the impression is to be taken and that or those on which it is to be set off are stationary and in which the means for taking the impression and setting it off consists of a rotatory cylinder mounted in a traveling carriage which is arranged to pass over both or all of the said articles. In working with machines embodying the said features of construction I have found that where sheets or slabs of glass or other brittle material which are not of uniform thickness at all parts have to be dealt with the inequalities of thickness cause imperfection of the setting off in consequence of the pressure of the surface of the cylinder being less on some parts of the surfaces on which the set off is received than on others. I have also found that where a pad of elastic or yielding material is placed between such sheets or slabs and the supporting-table of the machine for the purpose of correcting the said imperfection the said sheets or slabs occasionally break under the pressure of the cylinder, owing to the said pad yielding only at and near the part beneath that portion of the sheet or slab which for the time being is in contact with the setting-off surface of the cylinder.

Now the object of my said invention is to admit of use of the aforesaid machines for the purpose of setting off on sheets or slabs of glass or other brittle material of unequal

thickness at different parts without risk of the aforesaid consequences.

For convenience of reference in the following description of my invention I will term the aforesaid sheets of brittle material "the work" and the part of the machine on which during ordinary use the work is placed for receiving the set off the "feed-table," as in the aforesaid specification.

According to my said invention I provide for support of the work in the machine in such a manner that while the setting-off cylinder is acting on the front or surface of the work which is required to receive the set-off resistance to the pressure of the cylinder is produced on the back or reverse surface of the work only at the part immediately beneath that which for the time being is in contact with the said cylinder, and to insure equality of the pressure of the cylinder at all points of the part of the work in contact therewith, notwithstanding inequality in thickness of the said part, I combine an elastic or yielding element with the means by which the said pressure is resisted.

A convenient arrangement of parts whereby my said invention may be carried into effect is illustrated in the accompanying drawings.

Figure 1 of the said drawings is a plan view of certain portions of the aforesaid patented machine, the said portions being principally the feed-table and the setting-off cylinder, which latter is shown at the part of the machine where the damping-table (not illustrated) is situated. The said figure also illustrates the provision for the support of the work according to my present invention, the same being shown in connection with the feed-table. Fig. 2 is a section taken on the line A A, Fig. 1, showing the setting-off cylinder in the same position relatively to the feed-table as in Fig. 1. Fig. 3 is a section taken on the line B B, Fig. 1, but showing the setting-off cylinder in its advance traverse over the feed-table. Fig. 4 is a detail view showing in section, taken on the line C C, Fig. 1, a portion of the mechanism whereby resistance to the pressure of the setting-off cylinder is produced, as hereinbefore stated, on the back or reverse surface of the work.

In the following description the several parts of the accompanying drawings are referred to by the letters marked thereon.

In all the figures of the accompanying drawings the same letters of reference indicate the same parts, and such of the parts as are the same as those of the machine illustrated in the drawings of the aforesaid United States specification and are hereinafter referred to are marked with letters of reference the same as those on corresponding parts of the drawings of the said United States specification, the said parts being the following: The feed-table e , the setting-off cylinder i and its shaft i' and toothed wheels p q , the frames i^2 i^3 constituting the carriage supporting the said cylinder, portions of the side frames of the machine constituting the slides a^6 a^6 on which the cylinder-carriage travels, and the racks r r' with which the toothed wheels p q gear.

The aforesaid arrangement constituting the present invention consists mainly of the following parts: An apron or sheet b' , of the material known as "rubber printing-blanket" or other suitable flexible material, extended above the feed-table, a roller c' , covered or coated with elastic or yielding material c^2 , mounted beneath the said apron in bearings c^3 c^3 , carried by sliding supports c^4 c^4 , and means for causing the said roller to travel beneath the apron while the setting-off cylinder is traveling above it during working of the machine.

The apron b' passes over bars b^2 b^3 , supported by brackets d' d' d^2 d^2 d^3 d^3 , affixed to the said table by screws, and is secured at one edge to the bar b^2 by a clamping-bar b^4 and at the opposite edge to a roller f' , working in bearings formed on the brackets d' d' , and is kept in tension, as required, by engagement of a pawl f^2 with a ratchet-wheel f^3 on the said roller f' . The sliding supports c^4 c^4 of the bearings of the roller c' work between guides g g , secured to the feed-table e , and are connected together by rods h' h^2 and nuts h^3 h^3 , and the said bearings rest on springs j j , as shown in Fig. 4, which springs permit the roller c' to yield to pressure from above.

The traveling of the roller c' beneath the apron b' while the cylinder is traveling above it is provided for as follows: Below and at or near each end of the cylinder i is a pawl k' , which is normally held by a spring k^2 against a stop k^3 and has a projecting lug k^4 , which pawls k' are jointed to bars l l , carried by rods m m , secured at their ends to the supports i^2 i^3 of the setting-off cylinder i , and on the sides of the sliding supports c^4 c^4 of the bearings of the roller c' are secured plates bearing lugs n' n' n^2 n^2 , standing in the paths of motion of the lugs k^4 k^4 on the pawls k' k' , and secured to the guides g g on the table e in the paths of motion of the rounded noses of the said pawls are inclines o' o' o^2 o^2 , the effect of which inclines is to cause the lugs k^4 k^4 on the pawls k' k' to en-

gage with and to be disengaged from the lugs on the sliding supports c^4 c^4 of the pressure-resisting roller c' , as required, the axes of the setting-off cylinder i and of the said roller c' being in the same vertical plane, or approximately so, when the pawls k' k' are engaged with the lugs n' n' and the cylinder i is advancing over the work to produce the set-off. For the purpose of checking free motion of the sliding supports c^4 c^4 when released from engagement with the pawls k' k' springs s' s' s^2 s^2 are secured in the path of motion of the rods h' h^2 , connecting the said sliding supports.

The provision for insuring accurate lay of the work with the arrangement hereinbefore described consists of a bar t' , having a projection t^2 , forming a right angle with one of its edges and having slots in its end parts, in which slots are engaged clamping-screws t^3 t^3 , which are also engaged with slots in bars t^4 t^4 , secured to the brackets d' d' d^2 d^2 . The said slots and screws admit of adjustment of the said bar t' for variation of the lay when required.

u represents a tile placed on the feed-apron b' in position to receive a set-off from the cylinder i .

The action of the arrangement hereinbefore described is as follows: When during working of the machine the setting-off cylinder i has advanced to the feed-apron b' , the pawls k' k' are raised by the inclines o' o' , and on the said pawls descending after passing the said inclines the lugs k^4 k^4 pass between the lugs n' n' n^2 n^2 on the sliding supports c^4 c^4 of the roller c' , which during the further advance of the cylinder-carriage i^2 i^3 are caused to move forward with it by the bearing of the lugs k^4 k^4 against the lugs n^2 n^2 , the axes of the roller c' and of the cylinder i while the sliding supports c^4 c^4 are thus moved forward being in the same vertical plane as is shown in Fig. 3. Thus while the setting-off cylinder i is passing over the work to produce the set-off contact between the setting-off surface of the said cylinder and the work is maintained by the pressure-resisting roller c' under the feed-apron b' , which roller supports the work only at the part which is actually in contact with the setting-off cylinder, the other parts being supported only by the said feed-apron b' . The work, therefore, is not subjected during the setting off to any strain liable to produce fracture. The springs j j beneath the bearings of the pressure-resisting roller c' permit it to approach and recede from the setting-off cylinder i and to take an angular position relatively thereto in a vertical plane, and thus insure equality of pressure of the acting part of the said cylinder at all points notwithstanding irregularities of thickness at different parts of the work. After the set-off has been produced the sliding supports c^4 c^4 of the roller c' are freed from the cylinder-carriage i^2 i^3 by rise of

the pawls $k' k'$ over the inclines $o^2 o^3$, and the said supports and roller come to rest without shock, their momentum being absorbed by compression of the springs $s^2 s^2$ by the rod h^2 . On the reverse motion of the cylinder-carriage $i^2 i^3$, after it has reached the end of its forward stroke, the lugs $k^4 k^4$ on the pawls $k' k'$ again enter between the lugs $n' n' n^2 n^2$ on the sliding supports $c^4 c^4$ of the roller c' and by bearing against the lugs $n' n'$ draw the said roller backward until disengagement of the said lugs $k^4 k^4$ is produced by the inclines $o' o'$, when continued backward motion of the said roller and its supports is arrested by the springs $s' s'$, which act as described with reference to the springs $s^2 s^2$, the position of the said roller and its supports when so arrested being as shown in Fig. 2.

I claim as my said invention the following:

20 1. In a machine of the character described, a flexible support for the work, a setting-off cylinder operating over said support, a yielding roller operating beneath said support, and means carried by said cylinder for operating said roller simultaneously therewith.

25 2. In a machine of the character described, a flexible support for the work, a setting-off cylinder operating over said support, a pair of yielding slidable bearings, a roller journaled therein and operating beneath said support, and means carried by said cylinder and adapted to engage said bearings for operating said roller simultaneously with the operation of the cylinder.

30 3. In a machine of the character described, a flexible support for the work, a setting-off cylinder, operating means therefor, a pair of spring-pressed sliding bearings, lugs carried thereby, a roller journaled in said bearings, and means carried by said cylinder and adapted to engage said lugs for operating said roller simultaneously therewith in parallel relation.

35 4. In a machine of the character described, the combination with a setting-off cylinder operating upon the work, of a spring-pressed yielding roller operating beneath the work and in parallel relation with said setting-off cylinder, and means connected to said roller

and operated by said cylinder for simultaneously operating said roller therewith.

5. In a machine of the character described, a flexible support for the work, a setting-off cylinder, a pair of guides arranged at each side of said support, spring-pressed sliding bearings operating in said guides, a roller journaled in said bearings, and means connected to said cylinder and engaging said bearings for operating the same, imparting thereby a rotary movement to said roller simultaneously with the operation of said cylinder.

6. In a machine of the character described, a flexible support for the work, a setting-off cylinder, a spring-pressed roller, means connected thereto for operating the same, lugs carried by said means, pawls carried by said cylinder and adapted to engage said lugs for operating said means, means for bringing said pawls into operative engagement with said lugs, and means for releasing said pawls from their operative engagement with said lugs.

7. In a machine of the character described, a setting-off cylinder, a spring-pressed pressure-resisting roller, and means carried by the cylinder for operating said roller and cylinder simultaneously in parallel relation.

8. In a machine of the character described, a rotating horizontally-moving setting-off cylinder, a rotating longitudinally-moving spring-pressed roller, means for operating said roller simultaneously in vertical alinement, and means for discontinuing the rotary and horizontal movement of said cylinder and roller.

9. In a machine of the character described, a setting-off cylinder, a pair of spring-pressed sliding bearings operated thereby, a pair of rods for connecting said bearings together, a spring-pressed pressure-resisting roller journaled in said bearings, a flexible support for the work interposed between said roller and cylinder during said operation, and a position-bar for the work.
